UNITED STATES PATENT OFFICE

2,563,763

PROTECTIVE PAD FOR ATHLETIC SHOES

Frank Vietas, Bedford, Mass., assignor to A. R. Hyde & Sons Company, Cambridge, Mass., a corporation of Massachusetts

Application January 27, 1949, Serial No. 73,035

3 Claims. (Cl. 2—22)

11

This invention relates to a protective pad to be attached to the rear portion of the upper of an athletic shoe so as to project up above the top of the upper and be in position to protect the Achilles' tendon when the shoe with the pad is being worn. It is an object of the invention to provide a protective pad which is effective as a protective device, which is comfortable when being worn and which will not interfere with the freedom of ankle flexing of the wearer. The pad embodying the invention is characterized by protective layers of felt and canvas to provide a strong cushion, and lines of stitching arranged to stiffen the pad vertically but to permit a limited hinge movement about a horizontal axis not far from the lower edge of the pad. The pad is also adapted to be fastened to the upper of the shoe by short vertical lines of stitching which do not weaken the shoe at any point of special stress.

For a more complete understanding of the invention, reference may be had to the following description thereof and to the drawing, of which—

Figure 1 is a side elevation of a hockey shoe having attached thereto a pad embodying the invention.

Figure 2 is a section on the line 2—2 of Figure 1:

Figure 3 is a section on the line 3-3 of Figure 1;

Figure 4 is a rear elevational view of the pad shown in Figure 1;

Figure 5 is a section on the line 5-5 of Figure 4.

The protective pad 10 shown on the drawing

is composed of several layers. Preferably there is an inner layer 12 of felt and an inner layer 14 of canvas in face to face engagement with the felt. A cover layer 16 on the front or inside surface of the pad is preferably of thin soft leather, this being the cover layer which is next to the shoe and stocking of the wearer. A cover layer 18 on the rear or outer face of the pad is preferably of soft leather somewhat thicker than the leather in the layer 16, but other equivalent materials can be used for these cover layers.

As shown in Figure 4, the pad as a whole is substantially rectangular in shape, the long axis being vertical. A deep notch 20 is formed in

each side edge of the pad, these notches being directly opposite each other on a line substantially more than half way down from the top of the pad. The pad is provided with vertical lines of stitching 22 which extend from the top edge of the pad down to the level of the notches 20 and define a series of vertical panels 24. When the stitching is being done, the felt is strongly compressed along the lines of stitches by the presser foot of the machine and the stitches maintain the compression along such lines, as indicated in Figures 2, 3 and 5. The stitching thus serves to provide a certain amount of stiffness to the pad as a whole. This stiffness is preferably augmented by quilt stitching 26 on the middle one of the series of panels 24. As shown in Figure 4, the quilt stitching is in the form of crossed zigzag lines but any other suitable equivalent design can be employed.

26 At the lower ends of the vertical panels 24
two closely spaced horizontal lines of stitching
28 extend across the pad from one notch 20 to
the other. These horizontal lines of stitching
have the effect of making the pad somewhat
25 flexible on the horizontal axis defined by these
lines. In other words, the narrow horizontal
area 30 acts as an axis of flexing between the
portion of the pad above the notches 20 and the
smaller portion 32 of the pad below the notches
30 20. Quilt stitching 34 is preferably provided on
most of the area of the portion 32. This portion
has its lower corners beveled as at 36 forming
lateral wings 38 by which the pad may con-
veniently be attached to a shoe upper, the felt
35 being preferably omitted in these wings. As in-
dicated in Figure 1, short vertical lines of stitching
40 may be employed to tack the wings 38 to
the upper of the shoe, the pad being arranged
so that the lower edge of the pad comes sub-
stantially on a level with the top of the counter
40 stiffener 42 of the shoe. Thus the back of the
foot and leg is provided with continuous pro-
tection from the heel of the shoe up to the top
of the pad 10.

45 Any suitable means may be employed to hold the upper portion of the pad against the leg. For this purpose, the laces of the shoe may be passed through a pair of eyelets 44 mounted near the side edges of the pad, the end portions
50 being brought forward and tied in the usual

maner at 46. This secures not only the shoe but also the protective pad in place. The horizontal hinge element 30 thus comes just above the level of the ankle so that flexing of the foot at the ankle is not interfered with.

It is to be understood that the invention is not limited to the precise form and materials herein described, but may be varied within the scope defined by the following claims.

I claim:

1. A protective pad for attachment to an athletic shoe, comprising a layer of felt, a layer of canvas, front and back cover layers, spaced vertical lines of stitching through all said layers forming a series of vertical panels extending from the top of the pad more than half way to the bottom thereof, two closely spaced horizontal lines of stitching extending across said pad at the lower ends of said panels, and a notch in each side edge of the pad in line with said horizontal lines of stitching.

2. A protective pad for attachment to an athletic shoe, comprising a layer of felt, a layer of canvas, a cover layer of thin soft leather on the inner face thereof, a cover layer of thicker leather on the outer face thereof, vertical lines of stitching through all said layers forming a series of vertical panels extending from the top thereof more than half way to the bottom, quilt stitching on the middle panel of said series, two closely spaced horizontal lines of stitching extending across said pad at the lower ends of said panels, quilt stitching on the area below said horizontal stitching, and a notch in each side edge of the pad in line with said horizontal stitching.

3. In combination with an athletic shoe having an upper and a counter-stiffener, a protective pad comprising a layer of felt, a layer of

canvas and covering layers of soft leather, said pad having an upper portion and a lower portion defined by a pair of opposed V notches in the side edges thereof, the upper portion having a substantially greater height than the lower portion

5 10 and having spaced vertical lines of stitching forming a series of vertical panels, said lower portion having quilt stitching extending over the major portion thereof, two horizontal lines of stitching extending across the pad from one said notch to the other forming a narrow horizontal panel between said upper and lower portions, a line of stitching along each side edge of said lower portion attaching said pad to said shoe upper with the lower edge of the pad approximately on a level with the top of said counter stiffener, and an eyelet near each side edge of said upper portion of the pad adapted to receive the shoe laces whereby to hold the upper portion of the pad against the leg of the wearer.

FRANK VIETAS.
